UNITED STATES PATENT OFFICE.

JOHN UNczur, OF LINCOLN PARK, NEW YORK.

TRAIN-SIGNAL.

1,323,426.

Specification of Letters Patent.

Patented Dec. 2, 1919.

Application filed December 11, 1918. Serial No. 266,303.

To all whom it may concern:

Be it known that I, JOHN UNczur, a subject of the Government of Russia, formerly residing in the Province of Vilna, now residing at Lincoln Park, in the county of Monroe and State of New York, have invented certain new and useful Improvements in Train-Signals, of which the following is a specification.

10 The object of this invention is to provide a new and improved signaling device for the purpose of warning locomotive engineers if their engine has taken the wrong track in passing a switch.

15 This and other objects of the invention will be fully illustrated in the drawings, described in the specification and pointed out in the claim at the end thereof.

In the drawings:

20 Fig. 1 is a side elevation of a portion of the locomotive cab, showing a portion of the signaling device carried in place thereon.

Fig. 2 is a side elevation of the arm that overhangs the track and the support there-
25 for.

Fig. 3 is a plan view of a railroad track and a switch.

Fig. 4 is a plan view of a railroad track and a cross over.

30 Fig. 5 is an enlarged detail view of the overhanging arm and the upper end of the support partly broken away.

Fig. 6 is a detail view of the upper end of the support.

35 Fig. 7 is a vertical section through the overhanging arm on the line 7^x—7^x of Fig. 5.

Fig. 8 is a front elevation of a trigger placed on top of the locomotive cab.

40 Fig. 9 is a side elevation of the trigger.

Fig. 10 is a rear elevation of the trigger.

Fig. 11 is a diagrammatic view of the trigger, switch, battery and bell.

45 In the accompanying drawings, like reference numerals indicate like parts.

In the drawings, reference numeral 1 indicates a locomotive having a cab 2 thereon, on the edge of the roof of which is mounted an electric contact or switch 3 operated by a

50 trigger 4.

Reference numeral 5 indicates an over-
hanging arm which is intended to operate the trigger and 6 indicates a support there-
for. This support is hollow at the top as in-
dicated in Fig. 5 and the overhanging arm

55 has a bearing therein and is connected there-

to by a spring 7 which holds the arm in position to overhang the track or right of way at substantially right angles thereto, permitting the arm to swing in either direction. 60 The spring 7 is fastened at one end to the overhanging arm and at the other arm to the support and operates to draw the arm back to its normal position of overhanging the track when moved in either direction. The 65 overhanging arm is provided with a knife edge 8, which in the normal position of the arm rests in the shallow V-shaped recess 9 on the rim of the support, by which it is yieldingly held in place and from which it 70 must be lifted when it rotates in either direction.

The trigger is provided with a base 10 having a lug 11 thereon, on which is pivotally mounted a plate 12. On the plate 12 75 are provided two arms 13 and 14 pivotally connected to the lug 11 at 15 by a pin. Fas-
tened to the plate 12 is the lever 16 of spring
metal which on its lower end is bent at 18
and makes close contact with the vertical 80
wall of the lug 11. The center of rotation
15 is placed farther from the top of the lug
than it is from the vertical wall. As the
lever 16 moves to the left in Fig. 9 this
causes the lower end to be sprung outwardly 85
and causes a resistance to the movement
until the lever 16 has passed more than half
way between the vertical and horizontal,
after which the tendency of the spring to
straighten itself at 18 will force the lever 90
down with a snap into contact with the but-
ton 19 of the switch 3, pushing the button
down. This closes the circuit through the
wires 20, 21 and 22, battery 23 and bell 24,
and rings the bell and thus sounds the alarm 95
which warns the engineer that the signal has
worked because he is on the wrong track.
The plate 12 is provided with an arm 25
forming a bent lever therewith to which is
attached a cord 26 extending down into the 100
cab by which the engineer can pull the trig-
ger to its upright position again.

The operation of my device is as follows:

Assuming that the engine is running to
the left on Fig. 3 and takes the track at the 105
lefthand side of the switch, the lever 16 will
make contact with the arm 5 and will be
thrown thereby and will close the switch
and cause the bell to ring. But, if the en-
gine takes the right hand track at the 110
switch, the signal will not be disturbed be-
cause there is no overhanging arm at the

righthand track, or, if there is, its arm can be temporarily turned aside and held in inactive position. This will cause the signal to operate if the engine runs on the wrong 5 or lefthand track but the signal will not operate if the engine runs on the right track.

The resistance of the arm 5 to the turning movement will be such that it will hold its position and trip the lever 16 of the trigger 10 and cause the signal to operate but it will yield and swing if it is struck by the leg of the brakeman who may be near the edge of the car roof and thus makes contact with it. It will also be understood that the 15 arm 5 projects only a few inches inside of the outer end of the roof of the cab or car

over which it projects and will not project to the center of the track or to the center of the roof.

I claim:

A train signal device comprising a base, a lever pivoted thereon and normally extending upwardly therefrom, means carried thereon for normally holding said lever in an upright position, said means causing 25 said lever to move to a horizontal position after it has been moved part way from its upright position, a switch closed by said lever when in horizontal position, and an alarm operated through said switch.

JOHN UNCZUR.
